UNITED STATES PATENT OFFICE.

STERLING ELLIOTT, OF NEWTON, MASSACHUSETTS.

DESIGN FOR A SULKY-AXLE.

SPECIFICATION forming part of Design No. 22,691, dated August 8, 1893.

Application filed August 13, 1892. Serial No. 443,030. Term of patent 14 years.

To all whom it may concern:

Be it known that I, STERLING ELLIOTT, a citizen of the United States, residing in Newton, in the county of Middlesex and State of Massachusetts, have invented and produced a new and original Design for a Sulky-Axle, of which the following is a specification, reference being made to the accompanying drawing, forming a part thereof.

10 In the accompanying drawing, I have illustrated in a perspective view my newly designed sulky axle.

The leading feature of my design consists in a sulky axle having bifurcated ends turned 15 down and made to occupy substantially a single plane. There are two separated elements

a, b, arranged in parallelism and connected at several points by short cross pieces *c*. The axle is arched, the parts being in a single plane with the extremities extending downward as bifurcated ends, as illustrated.

What I claim is—

The design for a sulky axle, substantially as herein shown and described.

In testimony whereof I have signed my 25 name to this specification in the presence of two subscribing witnesses.

STERLING ELLIOTT.
